HANDLE FOR WINDOWS, DOORS AND THE LIKE

Harry M. Riegelman, Rolling Hills, Calif., assignor to
Ador Corporation, Fullerton, Calif., a corporation of
California

Filed Nov. 30, 1964, Ser. No. 82,831

Term of patent 14 years

(Cl. D10—8)

FIGURE 1 is a perspective view of a handle for windows, doors and the like embodying my new design, an associated window or door frame being shown fragmentarily in phantom lines for purpose of illustration and the handle of my new design being shown in a locking position with respect thereto;

FIGURE 2 is a left side elevational view of the handle shown in FIGURE 1;

FIGURE 3 is a rear elevational view of the handle shown in FIGURE 1; and

FIGURE 4 is a top plan view of the handle shown in FIGURE 1.

The dominant features reside in the solid line portions.

I claim:

The ornamental design for a handle for windows, doors and the like, as shown and described.
